UNITED STATES PATENT OFFICE.

GEORGE H. TATGE, CHARLEY MANZER, AND EARL MANZER, OF NORFOLK, NEBRASKA.

COLLAPSIBLE CRATE.

Application filed January 31, 1923. Serial No. 616,033.

To all whom it may concern:

Be it known that we, GEORGE H. TATGE, CHARLEY MANZER, and EARL MANZER, citizens of the United States, residing at Norfolk, in the county of Madison and State of Nebraska, have invented certain new and useful Improvements in Collapsible Crates; and we do hereby declare the following to be a full, clear, and exact description of the invention, such as will enable others skilled in the art to which it appertains to make and use the same.

This invention relates to a collapsible crate.

15 It is aimed to provide a novel construction which is exceedingly simple and inexpensive to manufacture and which does not sacrifice its capability of being compactly folded and readily and easily unfolded.

20 Another object is to provide such a crate essentially made from a plurality of flexibly connected frame units each similar in shape and preferably comprising a main slat and a plurality of cross slats rigid therewith.

25 A third object is to provide a construction in which the alternate frame units have their cross slats superimposed at their ends on the ends of adjacent cross slats and pivoted thereto.

30 Another object is to provide a construction having a foldable form ring and associated latch to prevent collapse of the frame units in unfolded or crate form.

Various additional objects and advantages 35 will be pointed out and otherwise appear from a consideration of the description following taken in connection with accompanying drawings illustrating one operative embodiment.

40 In said drawings:—

Figure 1 is a side elevation of the improved crate;

Figure 2 is a side elevation thereof in collapsed form;

45 Figure 3 is a vertical sectional view on the line 3—3 of Figure 1;

Figure 4 is a top plan view;

Figure 5 is a cross sectional view on the line 5—5 of Figure 1;

50 Figure 6 is a detail perspective view of one of the frame units, and

Figure 7 is a view in side elevation illustrating a modification in the construction of the lower end of the crate.

55 Like reference characters designate like or similar parts in the different views.

In carrying out the invention, the crate is essentially made from an even number of frame units 10, one of which is detailed in Figure 7. Each of these units consist of a main slat 11, usually vertically disposed, and transverse slats 12 and 13 at the top and bottom thereof, nailed thereto as at 14 or otherwise fastened. Intermediate these slats 12 and 13, one or more transverse slats 14^b may be provided which are nailed or otherwise fastened as at 15 to the main slat 11. Transverse slats 12, 13 and 14 project equidistantly on opposite sides of the main slat 11 as shown. All of the slats, 11, 12, 13 and 14 may be made of any material desired but are preferably made of wood. In the crate, the units 10 are so disposed that alternate transverse slats, 12, 13 and 14 at their ends will be superimposed on the adjacent ends of the respective cross slats. In such position, tie rods 16 are loosely passed through the ends of said transverse or cross slats 12, 13 and 14 in order to flexibly or hingedly connect said cross slats together. Each tie rod 16 may be provided at one of its ends with a head 17. The opposite ends of these heads may have nuts 18 threaded thereon so that they may be removed if desired, although it will be understood that the opposite ends of the rods may be upset if desired, in order to prevent accidental displacement of the rods from the crate.

In the unfolded or utile form of the crate, it will be generally of skeleton form. If desired, the bottom 19 may be disposed therein resting on alternate transverse slats 13. The bottom 19 is unconnected to the crate and therefore is removable, and it helps to maintain the crate in erected or utile form.

Also in order to prevent accidental collapse of the crate from utile form, a form ring 20, which may be of relatively stiff metallic wire, is disposed within the crate. By means of a staple 21 fastened to one of the main slats 11, said ring 20 is pivotally fastened in place. In order to prevent accidental folding of the ring 20, a spring latch 22 is fastened as at 23 to one of the main slats 11. Movement of the latch 22 is guided and limited by a staple or loop 24 fastened to the same main slat 11 as latch 22. The latch is offset or crooked as at 25 in order to receive the ring and it has a manipulating loop at 26.

The form of crate shown is particularly

adapted for use in connection with banana bunches either exposed or contained in sacks as preferred. This illustration is by way of example only since the principles are not 5 limited to that particular use and may be applied to crates generally.

In the utile form, the ring 20 is in a horizontal position and the bottom 19, if used, is in a horizontal position as shown. 10 In this form, the banana bunch or bunches is positioned within the crate and suitably tied or otherwise fastened thereto against loss or detachment therefrom during transportation. After use, the ring 20 is disengaged from the latch 22 and then folded flat against the main slat 11 bearing the staple 21. Also the bottom 19 is removed. 15 In this condition, the crate may be pressed from opposite sides so that the units may 20 pivot on the tie rods 16 and the structure will fold into the compact form shown in Figure 2 for storage or return transportation.

Instead of employing the bottom 19 and 25 other form ring 20 may be used adjacent the bottom of the crate as illustrated in Figure 7, thus presenting a form using two of said rings 20 one at the top and one at the bottom. Both form ring 20, their latches 22 30 and associated parts are similar. In such a form, the bananas or the like are preferably contained in a sack which is itself secured to the crate.

It is to be understood that changes in the details may be resorted to provided they fall within the spirit and scope of the invention. It is also to be understood that in practice the crate may be provided with either a top form ring and the solid bottom, or with top and bottom form rings, meeting the solid bottom, and that each frame unit may embody three or more transverse slats. 35 40

What is claimed is:—

A collapsible crate having an even number of frame units, each unit consisting of a main slat and transverse slats, said transverse slats extending equidistantly from opposite sides of the main slat, the transverse slats of alternate units being superimposed on the adjacent transverse slats and at the ends, tie rods passing through said ends parallel to the main slats and constituting pivots for the units, a form ring within the crate, means pivoting said ring to one of the main slats, and a fastening latch on said ring on another slat. 45 50 55

In testimony whereof we affix our signatures in presence of two witnesses.

GEORGE H. TATGE.
CHARLEY MANZER.
EARL MANZER.
